UNITED STATES PATENT OFFICE.

WILLIAM F. DUNN, OF PHILADELPHIA, PENNSYLVANIA.

LOCKING DEVICE FOR CARS AND THE LIKE.

999,969.

Specification of Letters Patent.

Patented Aug. 8, 1911.

Application filed February 15, 1911. Serial No. 608,768.

To all whom it may concern:

Be it known that I, WILLIAM F. DUNN, a citizen of the United States, residing in the city and county of Philadelphia, State of Pennsylvania, have invented a new and useful Locking Device for Cars and the Like, of which the following is a specification.

This invention relates to locking devices for doors of railway cars and more particularly to freight car doors and has for an object to provide means to lock the doors of a car in a secure and effective manner.

It has for a further object to provide a signal device, co-operatively positioned with respect to said locking means, whereby should any of the doors be unlocked the trainmen may be apprised of the fact.

It further consists of other novel features of construction, all as will be hereinafter fully set forth.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a section of a portion of a car showing a locking mechanism embodying my invention. Fig. 2 represents a section on line $x-x$, Fig. 1. Fig. 3 represents a portion of the top of a car showing a detail of construction. Figs. 4, 5 and 6 represent respectively, modifications of the operating mechanism of the locking device. Fig. 7 represents a section on line $y-y$, Fig. 6.

Similar numerals of reference indicate corresponding parts in the figures.

Referring to the drawings:—1 designates in the present instance the top of a freight car, of which 2 represents the sides and 3 the usual side doors slidably mounted in the guides 4, as will be apparent.

5 designates the battens of the doors 3, each of which carries in the present instance, a bushing 6, set therein and forming a socket with which the bolts 7 of the locking device are adapted to co-operate. These bolts 7 are properly guided with respect to these bushings 6 by means of the guide brackets 8 pref-

erably secured adjacent the doors and correctly located with respect to the said bushings.

9 designates a suitable guide bracket, for the bolts 7, secured by fastening devices 10 to the top 1 of the car. Suitable openings 11 are provided in the bracket 9 to guide the bolts 7 and permit free sliding movement for proper operation of the several parts. 65

12 designates as here shown a spring member secured at opposite ends to the respective bolts 7. Suitable securing devices 13 are utilized to connect the member 12 to the bolts 7. 70

14 designates an arm having a clip 15 preferably secured thereto by a pin 16 or the like and positioned to provide a suitable space to receive the spring member 12 to the said arm 14. It will be noted that the arm 75 14 is preferably, of sufficient length to project exterior of the top 1 when the locking bolts 7 are in released position. An opening 17 is of course located in the top 1 in alignment with the arm 14 in order to permit proper operation thereof.

18 designates a guide block secured by studs 19 or the like to the car frame 20, both the block 18 and frame 20 being apertured for the passage of the arm 14. 85

21 designates a suitable closure removably mounted in the opening 17, in the present instance having a hinge 22. This construction allows access to the arm 14 for operating purposes and also provides no obstruction on the top of the car. 90

Attention is directed to the fact that the lock operating mechanism is positioned beneath the running board 23 which is also provided with a hinged closure 24. This 95 closure 24 serves as a signal or indicating device by which the position of the locking devices may be determined, that is to say by a glance along the top of the car anyone may determine whether or not any of the 100 closures on the several cars are open.

25 designates a plurality of staples adapted to receive the usual car sealing device 26 by which the sealing of the car is effected to prevent tampering with the locks. 105

In Fig. 4 a modification of the lock operating mechanism consists as here shown, of a spindle 27 having a pinion 28 for engagement with the segment gears 29 mounted respectively on links 30. These links 30 110 have a pivotal connection 31 with the respective bolts 7.

In Fig. 5 another embodiment is shown wherein links 32 form a direct connection between the bolts 7 and an arm 33 which latter corresponds to the arm 14 heretofore described. A spring 34 encircles a portion of this arm 33 and bears at one end against the bracket 9, while its opposite end presses directly against the links 32 and causes the releasing of the bolts 7 as soon as the seal 26 10 is broken.

In Fig. 6 a further modification is shown, a toggle mechanism 35 is employed and joined by links 36 to the bolts 7 and by the pin 37 to the arm 38 which corresponds to the arm 14 heretofore described. The opposite side of the toggle 35 is connected by pins 39 independent of the arm 38 whereby relative movement of the parts is made possible.

In unlocked position the parts assume the position shown in Fig. 1 the arm 14 being held up by the spring 12 and retaining the closures 21 and 24 open. The latter 24 being located in the running board forms a signal which may be readily seen by a glance along the top of the car. This is an important feature since the caboose windows are alined with the top of the cars so that the top of the entire train is in view.

The locking of the doors is effected by pressing the arm 14 downwardly to drive home the bolts 7 after which the closure 21 is dropped and sealed and the closure 24 lowered as shown in Fig. 2. The parts are thus firmly and securely locked together and can only be released by breaking the seal 26. Should anyone tamper with the device and break the seal the spring release immediately opens the closures and gives a visible signal which can be seen from the caboose.

It will now be apparent that I have devised a complete unitary structure, simple in construction, effective in operation and by which the doors of a car may be securely fastened and further any tampering with or unlocking of the same will cause an indicator to be displayed warning the trainmen.

It will now be apparent that I have devised a novel and useful construction of a locking device for cars and the like which embodies the features of advantage enumerated as desirable in the statement of the invention and the above description, and while I have, in the present instance, shown and described a preferred embodiment thereof which has been found in practice to give

satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. In a device of the character stated, the combination with a car, of a plurality of bolts each adapted to engage and lock a door of said car, common operating mechanism therefor, signal means on the top of said car actuated by said operating mechanism and means to release said bolts when said signal means is free to operate.

2. In a device of the character stated, the combination with a car top, of a closure therein, car doors provided with sockets and locking devices consisting of an arm mounted beneath said closure, a plurality of bolts secured to said arm and adapted to engage said sockets and means to release said bolts.

3. In a device of the character stated, the combination with a car top, of a closure therein, car doors provided with sockets and locking devices consisting of an arm mounted beneath said closure, a plurality of bolts secured to said arm and adapted to engage said sockets and a spring for releasing said bolts.

4. In a device of the character stated, the combination with a car top, a closure therein, a running board on said top a closure therein alined with said top closure, of car doors provided with sockets, and locking devices consisting of an arm mounted beneath said closures, a plurality of bolts secured to said arm and adapted to engage said sockets and a spring for releasing said bolts.

5. In a device of the character stated, the combination with a car top, a closure therein, a running board on said top a closure therein alined with said top closure, of car doors provided with sockets and locking devices consisting of an arm mounted beneath said closures and adapted to project through said top in unlocked position, a plurality of bolts secured to said arm and adapted to engage said sockets and means for releasing said bolts.

WILLIAM F. DUNN.
